METHOD AND APPARATUS FOR THE
PERMANENT WAVING OF HAIR

Joseph Torres, Brooklyn, N. Y.

Application May 7, 1938, Serial No. 206,510

12 Claims. (Cl. 132—36)

This invention relates to the permanent waving of hair on the human head and has for its object the production of a new method and a new clamp for waving hair in the Croquignole fashion whereby the wave can be made closer to the head without danger of burning or otherwise injuring the scalp.

In previous methods and apparatus for the permanent waving of hair in the Croquignole fashion, it has been customary to divide the hair on the scalp into a plurality of strands, to pass each strand through a clamp and to coil the hair of each strand around a curler, which curler is located with its axis substantially directly above the slot in the clamp through which the strand of hair passes. The distance between the scalp and the first turn around the curler is normally from one and one-quarter to one and one-half inches or more from the scalp, and inasmuch as the permanent wave is imparted only to that portion of the hair which is wound on the curler, the distance of the first wave from the hair is in the order of one and one-quarter to one and one-half inches. The wave is therefore not as close to begin with as is desired, and as further hair begins to grow in from the scalp, the wave goes further and further away from the scalp and makes necessary another permanent wave in a few months, in order to wave the newly grown hair.

One of the principal objects of my invention is to provide an apparatus and method whereby the first wave is located nearer to the scalp than by other previous Croquignole methods and apparatus.

Another object of my invention is to provide a method and apparatus by which the first wave adjacent the scalp is not produced at the first turn around the curler but is produced by curling the hair over a section of the clamp between the curler and the scalp.

Another object of my invention is to provide a method and apparatus by which the wave of the hair can be put closer to the scalp than by previous methods and apparatus of Croquignole waving but by which the danger of burning or otherwise injuring the scalp or hair is greatly lessened.

Various other objects and advantages of my invention will appear as this description proceeds.

Referring now to the drawing which illustrates a preferred form of embodiment of my invention:

Figure 1 is a plan view of the clamp and curling apparatus which I use;

Figure 2 is a side view of the apparatus illustrated in Figure 1;

Figure 3 is a plan view of the apparatus illustrated in Figure 1;

Figure 4 is a sectional view along the line 4—4 of Figure 1;

Figure 5 is a sectional view along the line 5—5 of Figure 2;

Figure 6 is a sectional view of the apparatus showing the clamp with the heater in place thereon; and

Figure 7 is a perspective view of the clamp.

In the form of embodiment of my invention illustrated in the drawing, the clamp through which the strand of hair is passed is indicated at 1 and consists of a substantially trough-like member having a horizontal bottom wall 2 and a vertical side wall 3, which terminates in a curled lip or hair guide member 4. At each end of the clamping member 1, slotted brackets 5 and 6 are provided into which the ends of the rotatable curler member 7, around which the hair is wound, are inserted.

The parts 2, 3, 4, 5 and 6 are preferably made from one piece of sheet metal by suitable bending and stamping operations, but may be made in several pieces if so desired. To the bottom of the clamping member 1, suitable brackets 8 and 9 are secured to support the spring clamping member 10 which is held in closed position by the link 11 and cam-shaped thumb-piece 12.

The leaf spring 10 is preferably composed of a single length of spring steel which is bent to go around the pivot 8a and both leaves 10a and 10b brought together, as illustrated, to provide a spring which will retain its resiliency over long periods of time. A slot 10c is provided in the end of the spring member into which the link 11 fits to enable the spring to be clamped by the cam 12.

In applying a permanent wave in accordance with the apparatus and process of my invention, the hair is separated into a suitable number of strands on the scalp and a separate clamp member 1 is applied to each strand. The strand of hair is clamped between the spring member 10 and the vertical front wall 3 of the clamping member and held firmly in place by the closing of the cam member 12, as illustrated particularly in Figures 1 and 2. The front wall 3 of the clamping member may be provided with a rubber lining, if desired, and the spring clamp member 10 is preferably surrounded with a rubber tubing member 13, which holds the hair secure. Below the clamp member a slotted protecting shield 14 is slipped on the strand of hair over

the scalp and after the strand has been clamped in the clamp member 1, the hair is wound on the curler 7 beginning from the point farthest from the scalp and winding toward the scalp.

5 After the curler 7 has been wound to a position close to the scalp the squared end 7a of the curler is inserted in the squared slot 6a of the member 6, and the rounded portion 7b of the curler 7 is inserted in the slot 5b of the member 10 5; whereupon the handle 15 of the curler 7 may be turned to wind the strand of hair tightly on the curler 7, suitable ratchet means being provided inside the curler 7 adjacent the squared end 7a to hold the curler in the tightly wound position 15 for the hair.

In this position, the strand 16 of the hair is brought up from the scalp, illustrated at 17, between the vertical wall 3 and spring member 10 and over the roll 4 of the wall 3 where it is 20 wound in a plurality of coils 16b around the curler 7, as illustrated more clearly in Figures 4 and 5. The position of the curler shown is such as to hold the hair in a loop around the member 4. In this position, strand 16 is given its 25 first curl or bend 16a at the point where it passes over the roll member 4, which, with proper manipulation, can be located very close to the scalp to make the first curl or wave closer to the scalp than with previous clamps and methods for 30 hair waving by the Croquignole method.

Before rolling the strand of hair on the curler 7, it is preferably moistened with a suitable curling solution and after it has been rolled into the position illustrated in Figures 4 and 5, an 35 impervious cloth or pad 18, moistened with a suitable curling agent, is applied over the strand of hair and a heating element 19, preferably having suitable electric resistance heating means and connected through the conduit 20 to a suitable 40 source of current, is applied over the strand of hair and pad 18 and the clamp member 1, as illustrated in Figure 6. This heating element preferably consists of two part-circular members 19a and 19b mounted on a clamp pivoted around 45 the axis 21, so as to permit the members 19a and 19b to be separated for insertion over the strand of hair 16, suitable spring members being provided to clamp the heating elements 19a and 19b over the strand of hair and pad in the position 50 illustrated in Figure 6.

When the heat is applied to vaporize the curling solution and cause steam, most of the steam from the more densely wound portion 16b of the strand of hair goes into the pocket 1a formed by 55 the horizontal wall 2 and the vertical wall 3 of the clamping member 1, and inasmuch as these walls are preferably integral, none of the steam can escape in the direction of the scalp but must flow out the ends of the heater 19, where it cannot burn or injure the scalp. The smaller amount 60 of steam, generated at the point 16a where the strand passes over the rolled portion 4 of the clamping member, is prevented from touching the scalp by the rubber tube 13 surrounding the spring member 10 and the shield 14, and inasmuch as less steam is generated at the point 16a where the strand passes over the roll member 4, there is no danger of burning at this point.

The horizontal part 2 of the clamping member 70 1 is preferably secured by means of spacing rivets 2a to a space plate 22 in such a way as to provide a space for the circulation of air between the horizontal member 2 and the spacing plate 22, so that little heat is conveyed from the horizontal 75 member 2 to the spacing plate 22, and such heat

as is communicated is prevented from reaching the scalp by the shield 14.

By the use of the method and apparatus herein described, I am able to put a wave closer to the scalp than by any previous type of Croquignole apparatus and method used for hair waving and I am able at the same time to protect the hair and scalp from any possible danger of burning. 5

It is obvious to persons skilled in the art how the apparatus above described is to be used and that various modifications and changes can be made in the apparatus and method of using the same without departing from the spirit of my invention or the scope of the appended claims. 10

I claim:

1. In an apparatus for the permanent waving of hair, a clamp member having a vertically extending portion and a spring portion between which the strand of hair is clamped, means to support a curler back of the vertically extending portion, means to impart a bend to the strand of hair at the top of the vertically extending portion and means to clamp the strand of hair between the vertically extending portion and a clamp member. 20

2. In an apparatus for the permanent waving of hair, a clamp member having a horizontally extending portion, a vertically extending portion and a spring clamp portion cooperating with the vertically extending portion to clamp the strand 30 of hair between the vertically extending portion and the spring portion, means to support a curler back of the vertically extending portion and means to impart a bend to the strand of hair at the top of the vertically extending portion. 35

3. In an apparatus for the permanent waving of hair, a trough-like clamp member having a horizontally and a vertically extending portion, means to clamp the strand of hair between the vertically extending portion and a spring clamp member, means to support a curling member in the trough-like space between the horizontal and the vertical member and means to impart a bend 40 to the hair as it goes over the top of the vertical member. 45

4. As an article of manufacture a clamp for use in the permanent waving of hair comprising a trough-like member having a horizontally and a vertically extending portion, means to support a curling member in the trough-like portion, means to hold one portion of the curling member stationary while the other is being twisted to impart a roll to the hair, means to clamp the strand of hair between the vertically extending portion and a spring clamp member and means at the top of the vertically extending portion to impart a bend to the strand of hair between the curler and the scalp. 50

5. As an article of manufacture a clamp member for use in permanent waving comprising a 60

trough-like supporting member having a horizontally and a vertically extending wall, slotted means for each end of the trough-like member to receive a curling member and permit a roll to be imparted to the hair, a lip in the vertically 65 extending portion of the trough member for imparting a bend to the hair between the curler and the scalp, a double leaf spring member for clamping the hair against the vertically extending portion of the trough member and a cam for holding the clamping member in position. 70

6. In apparatus for the permanent waving of hair, a hair clamping device comprising a clamp, a member around which the hair may be bent at an angle of more than 90° immediately ad- 75

5 jacent the clamp, a curler on which the hair may be wound, and means to support the curler adjacent said member with the hair in a bend of more than 90° around said member, together with means to apply heat to the hair bent around said member and the hair wound on the curler.

6 7. Apparatus for the permanent waving of hair, as defined in claim 6, wherein the said member and the curler are of substantially the 10 same diameter.

8. In apparatus for the permanent waving of hair, a hair clamping device comprising a clamp, a member around which the hair may be bent at an angle of more than 90° immediately adjacent the clamp, a curler on which the hair may be wound adjacent the clamp, said curler being in position to hold the hair in a bend of more than 90° around said member, together with a heating clamp engageable around the hair bent 15 20 around said member and the hair wound on the curler to hold a heating pad thereagainst.

9. In an apparatus for the permanent waving of hair, a clamp comprising two members for clamping a strand of hair adjacent the scalp, 25 a member carried by one clamp member, extending parallel thereto and positioned immediately adjacent the clamping surface, a curler and means associated with said clamp for supporting the curler adjacent said member and parallel thereto on which curler a strand of hair passing from the clamp over said member to the curler may be wound, said member so positioned with respect to said curler that hair passing thereto is bent at an angle of more than 90°, a pad 30 to fit over said member and curler to hold the strand of hair against both said member and curler and a heating clamp to heat the pad and hair.

10. In apparatus for the permanent waving of hair, a clamp adapted to clamp a strand of hair adjacent the scalp, a curler carried by said clamp, 40

a member carried by said clamp positioned immediately adjacent the clamping surface over which the strand of hair passes from the clamp making a bend of more than 90° and from which the hair passes to and around the curler and 5 heating means engageable with the strand of hair to hold the same against said member and curler.

11. The method of permanently waving hair in the Croquignole fashion which comprises separating the hair into strands, moistening the strands with a permanent hair curling solution, applying a clamp member to each strand close to the scalp, rolling each strand into a tight curl, making a bend of more than 90° in the strand of 15 hair between the curled portion and the scalp immediately adjacent the clamping surface, and applying heat to the strand in such a way as to heat and vaporize the curling solution into both 20 the curled portion of the strand and the bent portion of the strand to cause a permanent wave in both the curled portion and the bent portion of the strand.

12. The method of permanently waving hair in the Croquignole fashion which comprises separating the hair into strands, moistening the strands with a permanent hair curling solution, applying a clamp member to each strand close to the scalp, rolling each strand into a tight curl, making a bend of more than 90° in the strand 25 of hair between the curled portion and the scalp immediately adjacent the clamping surface, leaving the bent portion of the strand exposed to the application of heat and further curling solution, 30 and applying heat to the strand in such a way as to heat and vaporize the curling solution into both 35 the curled portion of the strand and the bent portion of the strand to cause a permanent wave in both the curled portion and the bent portion of the strand. 40

JOSEPH TORRES.
